UNITED STATES PATENT OFFICE.

WILLIAM A. OLIPHANT, OF PETERSBURG, INDIANA.

FENCE-POST.

No. 914,867.

Specification of Letters Patent.

Patented March 9, 1909.

Application filed December 1, 1908. Serial No. 465,536.

To all whom it may concern:

Be it known that I, WILLIAM A. OLIPHANT, citizen of the United States, residing at Petersburg, in the county of Pike and State of Indiana, have invented certain new and useful Improvements in Fence-Posts, of which the following is a specification.

The object of the invention is to provide fence posts with improved metal bases so as to make a firm, strong, and durable foundation for the lower end of such posts.

The improved base is equally useful for application to old fence posts the ground ends of which may be decayed, as well as for new posts.

With these and other objects in view as will more fully appear as the description proceeds, the invention consists in certain constructions, arrangements, and combinations 20 of the parts that I shall hereinafter fully describe and then point out the novel features in the appended claims.

For a full understanding of the invention, and the merits thereof, reference is to be had 25 to the following description and accompanying drawings, in which:

Figure 1 is a vertical section of my improved fence post, the upper portion of the post being broken away and the foundation 30 being shown in section; Fig. 2 is a transverse sectional view on the line 2—2 of Fig. 1; Fig. 3 is a perspective view in detail of a part of the improved base; and, Fig. 4 is a perspective view of the remaining portion of the 35 base.

Corresponding and like parts are referred to in the following description and indicated in all the views of the drawings by the same reference characters.

40 The post 1 may be of any size, shape or construction depending upon the particular use or adaptation.

The base comprises a foundation 2, a series of plates 3 and 4, and loops 5 and 6. The 45 plates 3 and 4 are of similar construction and are arranged at the sides of the post near the lower end or foot thereof and are secured thereto in any substantial way. In the event of the post being of rectangular formation in horizontal section, four plates are provided and are secured in any substantial way to the four sides thereof. The upper ends of the four plates have inner flanges 7 which are toothed or serrated to bite into the post to 50 prevent both longitudinal and lateral displacement. The plates are apertured to re-

ceive suitable fastenings such as screws 8 which serve to secure the plates to the post. The lower ends of the plates have outer flanges 9 which are notched at 10 intermediate of their ends. The several plates project below the end of the post to be embedded in the material forming the foundation 2.

The loops 5 and 6 are preferably of stout wire, the upper ends of the side members 65 being engaged with the lower ends of the projecting portions of the plates extending below the posts. Each of the loops is formed of a length of wire bent into approximately U-form, the ends of the side members being 70 passed through openings in the projecting ends of the plates and bent so as to engage with said plates and retain said loops in place. The end portions of the loops enter the notches 10 of the flanges 9, thereby holding the loops in longitudinal alinement with the post. The loops have a right angular arrangement and one loop is longer than the other as indicated most clearly in Figs. 1 and 2.

When setting a post provided with a base substantially as herein indicated, an excavation is formed in the ground of a size to receive the base and leave a space at the bottom and sides thereof. The post is placed 85 in position with its base entered in the hole or excavation and the material forming the foundation, such as concrete, is placed in the hole and tamped therein about the base, and after said material hardens or sets the position of the post becomes fixed. It is observed that the projecting ends of the plates are embedded in the material forming the foundation, thereby preventing any possible play between the post and its base. The 95 outer flanges 9 serve the two-fold purpose of preventing relative lateral play of the loops 5 and 6 and to secure firm anchorage of the plates in the material forming the foundation 2.

100 From the foregoing description, taken in connection with the accompanying drawing, it will be seen that I have provided a very simple, durable and efficient construction of fence post which may be cheaply made and 105 when set will be firm in place and capable of withstanding hard use. As the wooden portion of the post, if wood be used for the post proper, is held out of contact with the soil, it will not be subjected to decay as would 110 otherwise be the case, and will therefore last a considerable time.

The invention is not restricted in its use and may be applied to posts for telephones and telegraph wires or for other uses.

Having thus described the invention, what I claim as new is:

1. A fence post provided upon opposite sides with plates having flanges at their lower ends and having said flanges notched at a point between their ends, and a loop 10 having its terminals engaged with said plates and the end portions of the side members fitted in the notches of said flanges to retain the loop in the required position.

2. In combination with a post, plates secured to opposite sides of the post and having end portions extended beyond the end of the post and provided with openings and outer flanges the latter being notched, and a loop having the end portions of its side members engaged with the said openings and with the notched flanges to hold the loop in the required position.

3. In combination with a post, plates secured to opposite sides thereof and having end portions extended and provided with openings and outer flanges the latter formed with notches, and a loop having its side members embracing outer sides of the projecting ends of said plates and fitted in the notches 25 of the flanges, the terminal portions of said side members projecting through the openings of said plates and bent against the inner sides thereof.

4. In combination with a post, plates secured to opposite sides thereof and having end portions extended and provided with openings and outer flanges the latter formed with notches, and loops having their side

members embracing outer sides of the projecting ends of said plates and fitted in the 40 notches of the flanges, the terminal portions of said side members projecting through the openings of said plates and bent against the inner sides thereof.

5. In combination with a post, plates secured to opposite sides thereof and having end portions extended and provided with openings and outer flanges the latter formed with notches, and loops arranged at right angles and having their side members 50 embracing outer sides of the projecting ends of said plates and fitted in the notches of the flanges, the terminal portions of said side members projecting through the openings of said plates and bent against the inner sides 55 thereof.

6. In combination with a post, plates secured to opposite sides thereof and having end portions extended and provided with openings and outer flanges the latter formed 60 with notches, and U-shaped loops arranged at right angles and one being shorter than the other and having their side members embracing outer sides of the projecting ends of said plates and fitted in the notches of the 65 flanges, the terminal portions of said side members projecting through the openings of said plates and bent against the inner sides thereof.

In testimony whereof I affix my signature 70 in presence of two witnesses.

WILLIAM A. OLIPHANT. [L. S.]
